CARRIER FOR FULL-FASHIONED KNITTING MACHINES

Frederick A. Redday, Philadelphia, Pa., assignor to Fred C. Good & Sons, Philadelphia, Pa., a partnership consisting of Fred C. Good, Fred G. Good, and Raymond J. Good, all of Philadelphia, Pa., and Curtis Sooy, Willow Grove, Pa.

Application October 26, 1936, Serial No. 107,504

2 Claims. (Cl. 66—126)

This invention relates to knitting machines of the full-fashioned type, and is concerned primarily with the thread carriers which feed thread to the knitting needles.

5 At the present time certain types of work, such as the making of a reinforced heel in hosiery requires the use of a transversely moving thread carrier which feeds a pair of yarns to the sinker bed in spaced relation to one another. The desirability of such an arrangement has been well recognized in the knitting art. Ordinarily these 10 yarns which are fed to the needles in the sinker bed have a spaced relation which is measured by the number of needles, and which spaced 15 relation is maintained throughout the knitting operations.

Accordingly, thread carriers have been proposed which are formed with spaced tubes through which the yarns pass to determine their relative positions as they are being fed to the needles. However, whenever the spaced relationship of the yarns is to be varied to accommodate different types of work, it has been necessary to change the thread carriers, which is an 25 operation carried out only with a considerable degree of difficulty and annoyance.

With the foregoing conditions in mind, this invention has in view as its foremost objective the provision of a thread carrier which is designed for use with full-fashioned knitting machines, and which thread carrier is effective to feed a pair of threads in spaced relation to the needles in the sinker bed of the knitting machine. In accordance with this invention the 30 carrier may be adjusted to vary the space between the yarns, and thereby adapt the carrier to work of different types.

In carrying out this idea in a practical embodiment, this invention contemplates the use 40 of a thread carrier which is formed with a bifurcated or forked portion to provide a pair of legs. Each of these legs carries a tubular element which is in communication with a groove formed in each leg. The carrier is made from an appropriate metal which has the ability to obtain 45 any formation into which it may be bent. By spreading the legs the desired distance apart, as by under the influence of a proper tool, the proper spaced relation between the tubular elements through which the yarn passes may be obtained in the carrier adapted to different types 50 of work.

A somewhat more detailed object is the provision of a thread carrier of the type above noted, 55 in which the bifurcated or forked construction

is peculiarly designed to impart to the legs the ability to be spread or contracted a required amount, and maintained in the adjusted position. This is attained by providing the body of the thread carrier with an elongated slot which terminates in an enlarged recess.

The material defining the body portion and legs is thinned out in the direction of the tubular elements. This enlarged recess readily adapts itself to having a tool inserted therein for the 10 purpose of spreading the legs.

With the use of a thread carrier which is adjustable, as above noted, it is possible to make more varied styles of hosiery on a full fashioned machine without changing or adding attachments. Moreover, the thread carriers are particularly adapted for making reinforced welts, 15 finer seams and stripes in the hosiery product.

Due to the fact that the need for changing the thread carriers is obviated, speed of production is increased, and a longer life imparted to the carrier tubes, in that these parts, as well as the needles, are not damaged incident to any changing of the carriers, the latter having been 20 eliminated.

A further advantage lies in the elimination of the liability of breaking or nicking the sinkers, which causes wear in the sinker bed and frequently results in sinker lines in the hosiery.

Various other more detailed objects and advantages of the invention will in part become apparent, and in part be hereinafter stated, as the description of the invention proceeds.

The invention, therefore, comprises a thread carrier designed for use with a full fashioned 35 knitting machine, and which carrier consists of a main body portion formed with a bifurcated or forked construction which provides a pair of spaced legs. Each of these legs is formed with a groove, and carries a tubular element which is 40 in communication with the groove. The carrier is made from an appropriate material imparting the ability of the legs to maintain any adjusted relative position.

For a full and more complete understanding of 45 the invention, reference may be had to the following description and accompanying drawing, wherein

Figure 1 is a plan view of a thread carrier made in accordance with the precepts of this 50 invention.

Figure 2 is a longitudinal section taken about on the plane represented by the line 2—2 of Figure 1.

Figure 3 is a view in perspective of the various 55

elements entering into the mounting of one of the tubular members in the carrier. This view brings out the parts in an exploded relationship, and

5 Figure 4 is a perspective showing, bringing out the relationship of the thread carrier to the sinker bed of a full fashioned knitting machine.

10 Referring now to the drawing, wherein like reference characters denote corresponding parts, and more particularly to Figure 4, the sinker bed 10 of a knitting machine is identified by the reference character 10. Carried by the sinker bed 10 are the alternately disposed sinker, and dividers, which are referred to generally by the reference 15 character 11. The knitting needles are identified at 12, and are shown as being disposed between the sinkers and dividers 11.

20 A thread carrier, which is referred to generally by the reference character C, is mounted to move transversely across the sinker bed during the knitting operations, and feed a pair of threads, identified as 13 and 14, to the needles 12 in a spaced relationship that is maintained throughout the knitting operation; the relationship between the threads 13 and 14 usually being measured by a given number of the needles 12.

25 Referring now more particularly to Figures 1, 2 and 3, the construction of the thread carrier C is illustrated in detail, and it is noted at this point that this thread carrier may be made from any appropriate material having the ability to maintain a position into which it may be deformed. In the preferred embodiment, the thread carrier is made from annealed spring 30 steel which has this property to a high degree.

35 As shown in Figure 1, the carrier C is provided with a pair of openings, indicated at 15, which are availed of in assembling the carrier with the proper parts of the knitting machine. A slot 16 extends from one end of the carrier, and terminates in an enlarged recess 17; the slot 16 and recess 17 together defining a bifurcated construction which takes the form of the spaced legs 18 and 19.

40 45 It is notable that the legs 18 and 19 are reduced in thickness in a direction away from the recess 17. Each of the legs 18 and 19 is provided with a groove 20 which terminates in a partially cylindrical opening indicated at 21, and which houses a sleeve element 22. The latter is of a split 50 construction and embraces a tubular member 23 which is in communication with the groove 20. The construction of each of the legs 18 and 19, comprising the parts 21, 22 and 23, provides a proper mounting for assembling a tubular element 23 with each of the legs.

55 At the lower extremities each of the legs 18

and 19 is slightly deformed to provide a bend, indicated at 24. These bends serve the purpose of properly disposing the tubular elements 23 with respect to the sinker bed.

5 In the full line showing of Figure 4 the tubular elements 23 are shown in such a relative position as will provide for a spacing of the threads 13 and 14 six needles apart. When the legs 18 and 19 are contracted the tubular elements 23 assume the inner dotted line positions, keeping the 10 threads 13 and 14 four needles apart. If the legs 18 and 19 are expanded into the outer dotted line position the tubular elements 23 will be eight needles apart.

15 The expanding actions may preferably be carried out by inserting an appropriate tool in the recess 17 and the slot 16, while the constriction of the legs 18 and 19 may be carried out in an obvious manner. It is evident that the relative 20 positions of the tubular elements 23 of the legs 20 18 and 19 are capable of wide variation, and are not limited to the particular number of needles above specified. Moreover, the bend 24 will be varied to accommodate the thread carrier to any 25 particular type of work.

While a preferred specific embodiment of the invention is hereinbefore set forth, it is to be clearly understood that I am not to be limited to the exact construction illustrated and described, because various modifications of these 30 details may be provided in putting the invention into practice within the purview of the appended claims.

I claim:

1. In a full-fashioned knitting machine, a 35 thread carrier comprising a main body portion formed from a metal having the ability to retain any formation in which it may be bent, said body portion having a bifurcated construction defining a pair of legs which are integral with 40 the body portion, each of said legs being grooved, and a pair of tubular elements carried by said legs in spaced relation to each other, each of said tubular elements being in communication with the groove in the respective leg. 45

2. In a full-fashioned knitting machine, a 50 thread carrier comprising a main body portion formed with means for assembling the same to the appropriate parts of the knitting machine, said body portion being made from an annealed spring steel and formed with an elongated slot 55 terminating in a recess, said slot and recess defining a pair of spaced legs, each of said legs being formed with a groove, and a tubular element carried by each of said legs and in communication with the groove therein. 55

FREDERICK A. REDCAY.
